UNITED STATES PATENT OFFICE

2,507,249

GOLF BAG

Nick Dorazio, Baltimore, Md.

Application October 16, 1946, Serial No. 703,577

5 Claims. (Cl. 150—1.5)

1

This invention relates to improvements in golf bags.

An object of the invention is to provide an improved golf bag having a rigid skeleton frame and a detachable cover therefor adapted to be supported by and secured to said frame.

Another object of the invention is to provide an improved golf bag having a skeleton frame including a base and split vertical supporting members secured thereto, and a cover therefor detachably held between said split members with separable fasteners, together with separator means insertible in said frame and cover for providing separate compartments in which the several golf clubs will be received.

A further object of the invention is to provide an improved form of golf bag including a frame and detachable cover therefor having separate pockets incorporated therein for holding the various golf clubs, each in its own pocket.

A still further object of the invention is to provide an improved form of golf bag having a skeleton frame and a washable cover therefor detachably secured thereto, said bag having means for carrying club head protecting hoods and a supply of golf balls and tees, and a small umbrella.

Another object of the invention is to provide an improved golf bag which will be highly efficient in use, and relatively inexpensive to manufacture and produce.

Other objects will appear as the description proceeds.

In the accompanying drawings which form a part of this application,

Figure 1 is a perspective view of the completed golf bag;

Figure 2 is a perspective view of the golf bag frame for supporting the cover;

Figure 3 is a front elevation of the outside of the detachable golf bag cover;

Figure 4 is a front elevation of the inside of the detachable golf bag cover;

Figure 5 is a perspective view of the separator plates used to divide the golf bag into compartments, and

Figure 6 is a detail view partly in section of the golf bag frame and cover showing the securing means for holding the cover on the frame.

Like characters of reference are used throughout the following specification and the accompanying drawings to designate corresponding parts.

In carrying out the invention, there is provided a base or bottom plate 1 generally elliptical

2

in shape, to which a plurality of V-shaped metal frame strips 2 are secured, the inner arms 3 of said strips 2 being secured to the metal reinforcing hoops 4 and 5 by welding or in any other desired manner, said hoops being positioned at the upper ends of said strips 2 and at a point intermediate the ends of said strips 2. Inverted cup-shaped fastening clips 6 are provided to slip over the upper ends of the V-shaped frame strips 2 and 3 after the detachable golf bag cover 7 has been inserted between said V-shaped frame strips.

The bag cover 7 will be made from leather or from canvas or a washable material, and will be of rectangular shape, approximately the same height as the V-shaped frame strips 2 and 3, and of a length to completely encircle said hoops 4 and 5.

Positioning slots 8 and 9 will be formed through the upper and lower edges of the bag cover 7 to permit the outer frame arms or strips 2 to extend therethrough when placing the cover on the frame, after which the fastening clips 6 will be placed over the upper ends of said pairs of frame arms 2 and 3.

Female snap fastener elements 10 will be carried by the lower edge of the bag cover 7 and will snap on the male fasteners 11 on the base or bottom 1.

Male and female snap fastener elements 12 and 13 will be supported by the upper edge of said bag cover 7 to lock over the fastening clips 6 when positioned over the upper ends of the frame arms 2 and 3.

Spaced straps 14 and buckles 15 will be disposed on the opposite ends of the bag cover 7 to be secured when the cover is in position, and cooperating male and female snap fasteners 16 and 17 will also be secured or positioned along said vertical ends of the bag cover 7, to further hold and support the same on said frame strips.

Individual pockets 18 will be provided in spaced relation in vertical position to support the handles or grip portions and shanks of the golf clubs 19, or if desired, the separator plates 20 extending at right angles to each other may be inserted within the hoops 4 and 5 of the bag frame to form a plurality of parallel vertical compartments in the golf bag.

Pockets 22 and 23 having "zipper" closures 24 and 25 respectively are provided on the outer surface of the bag cover 7 to hold hoods for the clubs and for holding extra golf balls and tees.

Suitable fastening bands or rings 26 and 27 will be disposed in vertical relation on the outer

surface of the golf bag cover 7 to support a small umbrella 28. An adjustable carrying strap 29 will be suitably secured to the outer surface of said cover.

From the foregoing description, it will be seen that a highly efficient form of golf bag will have been devised and provided which may be taken apart when desired or at the end of a season and the cover washed or suitably cleaned.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention, what I claim as new and desire to secure by Letters Patent of the United States is:

1. A golf bag comprising a base member and 20 vertically spaced hoops, V-shaped frame strips distributed around said base and hoops in spaced parallel relation, said strips having inner and outer legs, said inner legs being rigidly secured to said base and hoops, a cover having vertically spaced apertures to receive said outer legs, and means for detachably securing said cover to said base member and the top hoop whereby said cover is wrapped around said base and hoops and supported between the inner and outer legs 30 of said frame strips.

2. A golf bag comprising a frame therefor, a two-part brace joined together at the bottom and free along the vertical length thereof, means securing said brace to said frame, and a cover 35 removably seated on one part of said brace member and engaging the other part, said cover including means for removably securing said cover on said frame, said brace consisting of a pair of vertical strips joined at their bottoms and providing a V-shaped space along the vertical length thereof for supporting said cover therein.

3. A golf bag comprising a base, a vertical V-shaped brace having inner and outer legs and secured to said base, a plurality of reinforcing hoops secured to the inner leg of said brace along the vertical length thereof, and cover means removably retained on the outer leg of said brace and engaging the inner leg member, said cover and base including attaching means thereon.

4. The combination of claim 3 wherein said cover includes spaced, aligned slots, said outer leg extending through said slots for retaining said cover in position.

5. The combination of claim 3 wherein said brace includes fastening clips mounted on the spaced upper extremities to retain said cover in position, said cover including a flap bendable over said clips and secured to the inner surface of said cover.

NICK DORAZIO.
